Application December 22, 1939, Serial No. 310,571

15 Claims. (Cl. 68—23)

This invention relates to washing and drying machines, and more particularly to continuous washing and drying machines.

An object of this invention is to provide a machine of this type wherein bags or like articles may be washed and dried, the bags or like articles having had stored therein raw sugar or similar sticky food products.

Another object of this invention is to provide a machine of this type with automatic means for regulating the flow of wash water relative to the amount of material being washed from the bags.

A further object of this invention is to provide a machine wherein the material washed from the bags may be recovered and refined.

A still further object of this invention is to provide a machine of this character wherein the material is removed by forcing water through the bags by centrifugal force and subsequently cutting off the driving force in such a manner that the bags will move longitudinally of the machine, the movement of the bags through the machine being dependent upon the speed of rotation of the bags relative to the machine.

A further object of this invention is to provide a means for varying the operation of the machine so as to effect movement of the bags therethrough.

A further object of this invention is to provide a washing and drying machine in which the washing and drying is carried on more efficiently and continuously instead of intermittently and in batches as at present.

With the foregoing and other objects in view, the invention will be more fully described hereinafter, and will be more particularly pointed out in the claims appended hereto.

In the drawings, wherein like symbols refer to like or corresponding parts throughout the several views,

Figure 1 is a detail side elevation of a washing and drying machine embodying this invention.

Figure 2 is a longitudinal section, partly broken away of the machine.

Figure 3 is a sectional view taken on the line 3—3 of Fig. 2.

Figure 4 is an enlarged fragmentary sectional view taken on the line 4—4 of Fig. 2.

Figure 5 is an enlarged fragmentary sectional view taken on the line 5—5 of Fig. 2.

Figure 6 is a fragmentary vertical sectional view through the drying and ironing means used with this invention.

Figure 7 is a diagrammatic view of the electric circuit used with the motor.

Figure 8 is a fragmentary sectional view of a modified form of washing drum.

Figure 9 is a fragmentary side elevation of another form of controlling means for the washing drum.

Referring to the drawings, the numeral 10 designates a base member, and the numeral 11 designates a drum or stationary housing which is disposed above the base 10. The drum 11 comprises a cylindrical body 12 and end walls 13 and 14. The end wall 13 has an opening 15 therethrough which is eccentric to the axial center thereof, and the end wall 14 is provided with an opening 16 coaxial with the body 12.

The body 12 has secured to the lower side thereof of a pair of segmental angle members 17 to which a plate 18 is secured. The lower ends of the plates 18 are substantially horizontal, and are secured to angle bars 19 which are also secured to a pair of I-beams 20. One end of each beam 20 is pivotally secured on a bearing 21 which is fixed to the base member 10 so as to thereby pivotally secure one end of the housing or drum 11 to the base 10. In the present instance the base 10 is constructed in the form of a pair of I-beams shown more clearly in Fig. 3. A plate 22 is connected to the opposite ends of the beams 20, and a threaded shaft 23 loosely engages through the plate 22. A lower end of the shaft 23 is pivotally mounted on a bearing 24, and a nut 25 is threaded onto the shaft 23 and bears against the lower side of the plate 22 so as to support the housing 11 in a predetermined angle relative to the horizontal. Adjustment of the nut 25 will raise or lower the upper discharge end of the housing 11.

An inner rotatable centrifugal cylinder 26 is disposed within the housing 11, and is provided for a portion of the length thereof with openings 27 which are inclined outwardly in the direction of rotation of the cylinder or drum 26 so that as the cylinder 26 rotates water or other liquid within the lower portion of the outer housing 11 will be driven in through the openings 27 with such force as to form a plurality of jets for discharging the water or other liquid against the bags disposed within the cylinder 26. From a point substantially midway of the length of the cylinder 26 to the upper or discharge end thereof, the cylinder 26 is provided with another series of openings 28 which are inclined oppositely from the openings 27. These openings 28 provide a suction means in the drying portion of the cylinder 26, as well as in the upper portion of the submerged part of the cylinder 26 whereby the water

or other liquid is centrifugally extracted from the bags. The level of the liquid or water in the outer drum or housing 11 is such that from substantially the center of the drum or cylinder 26 to the lower or intake end, the wall of the drum 26 is submerged in the water or other liquid, and from the center of the drum 26 to the upper or discharge end thereof, the drum 26 is disposed out of the water.

The inner drum 26 is provided with a pair of annular rings or bearing tracks 29 which are fixed to the exterior of the drum 26 adjacent each end thereof, and the tracks 29 engage rollers 30 having trunnions 31 engaging in bearings 32 which are fixed to the inside of the outer housing 11. The tracks 29 are held against endwise movement by means of rollers 33 which are rotatably carried by shafts 34 fixed in the bearings 32. In the present instance the rollers 33 are disposed on the lower side of the tracks 29 so as to take up the thrust due to the inclination of the drum 26 and the housing 11.

A plurality of arcuate plates 35, 36 and 37 are disposed within the housing 11 exteriorly of the drum 26 and are spaced apart in the washing zone 41 and serve as baffles to retain the water or other liquid within the washing zone 41. The plates or baffles 35, 36 and 37, are provided with flanges 38, 39 and 40, respectively which are secured to the inner surface of the outer housing 11 so as to maintain the plates or baffles in position. The plate or baffle 35 engages between a pair of rings 42 and 43 which are provided with flanges 44 and 45, respectively which are secured to the exterior of the drum 26. The plate or baffle 36 engages between a pair of rings 46 and 47 having flanges 48 and 49, respectively which are secured to the drum 26. The plate or baffle 37 engages between a pair of rings 50 and 51 having flanges 52 and 53, respectively, which are secured to the drum 26. The baffle rings hereinbefore described coat with the baffles in retaining the water in the space between the baffles and also within the washing zone 41. The baffles 35, 36 and 37 are slightly less than semi-circular, as shown in Fig. 3, and also serve the purpose of providing a means whereby the clean fresh water entering the drum from the inlet pipe 54 is prevented from flowing directly to the outlet pipe 60.

Water is discharged within the washing zone 41, and in the present instance between baffles 35 and 36 through a water intake pipe 54 which is connected to a boss 55 carried by the outer drum or housing 11. A valve 56 is interposed in the intake pipe 54, and is preferably of the solenoid operated type, being connected by wires 57 and 58 to a suitable water control means as will be hereinafter described. The level of the water in the housing 11 is regulated by means of an outlet valve 59 which is interposed in an outlet pipe 60 connected to the lower portion of the housing 11, as shown in Fig. 2. The valve 59 which is in the pipe 60 is operated by means of a float 61 which is disposed in the housing 11, and is connected to the valve 59 by means of a linkage 62, 63 and 64. The link 62 is pivotally mounted intermediate its ends on a support 65 secured to the end wall 15 of the housing 11, and the link 64 is pivotally mounted on a support 66 carried by the valve 59. The valve plug or plunger 67 is pivotally connected to the link 64 intermediate the ends thereof, so that vertical rocking of the link 64 will move the valve plug or plunger 67 to open or closed position.

The washing and drying drum 26 is provided on the interior thereof with a helical bag carrier 68 which extends throughout the length of the drum 26. From the intake end of the drum 26 to substantially the center thereof, or for the length of the washing chamber or zone 41, the pitch of the helical carrier is substantially greater than the pitch thereof in the drying zone or chamber 69. The variation in the pitch of the carrier in the two zones provides for a slower movement longitudinally of the drum 26 within the drying zone than within the washing zone, so that the bags will be comparatively dry when discharged from the discharge end of the drum 26.

The drum 26 adjacent the upper or discharge end thereof is provided with a pulley or sheave 70 having a plurality of V-shaped annular grooves 71 within which V-belts 72 engage. The belts 72 are trained over a driving pulley or sheave 73 which is fixed to a motor shaft 74 operated by a motor 75. The motor 75 is mounted on a platform 76 secured to a pair of supporting beams or bars 77 which are fixed to the beams 20. The pulley 70 is disposed outwardly of the end wall 14 of the housing 11, as shown in Fig. 2. A stationary cylindrical receiving member 78 is disposed loosely about the upper or discharge end of the drum 26, and is supported in outwardly extended position to the drum 26 by means of brackets 79 which are fixed to the end wall 14. The cylindrical member 78 is provided with an end wall 80 having a discharge opening 81, and the interior of the cylindrical member 78 is also provided with a helical rib 82 having a relatively shallow pitch so that when the bags are discharged from the upper end of the drum 26 and are rotating under centrifugal force the bags may continue to rotate, but the stationary helical rib 82 will provide a means whereby the centrifugal or rotary force of the bags will be dissipated.

The centrifugally dried bags are discharged or taken manually from the receiver 78 onto a drying table or platform 83 forming part of a drying and ironing structure generally designated as 84. The drying member 84 comprises a lower upwardly flared inverted hood 85 having a hot air duct 86 connected to the lower or apex thereof. The duct 86 is adapted to be connected to a suitable source of hot air supply (not shown) whereby the heated air is forced through the duct 86 and through the hood 85. The hood 85 at its upper end is provided with a perforate plate 87 which is coplanar with the table 83 and may be formed as a continuation of the table 83. A plurality of lower hollow heating rollers 88 are rotatably carried by the hood 85 and are adapted to project partly through the plate 87 so as to contact with the bags disposed on the upper surface of the plate 87.

An upper substantially conical hood 89 is disposed above the plate 87 and above a series of upper hollow heating rollers 90 which are rotated by means of a chain or flexible drive member 91. The upper rollers 90 are adjustable relative to the lower rollers 88, being carried by bearings 92 having slots 93 which permit vertical adjustment of the upper rollers 92. If desired the upper rollers may be spring-pressed in any suitable manner so as to place these rollers under tension. A lower fan 94 is connected to the duct 86, and is adapted to force the air upwardly through the hood 85, and an upper suction fan 95 is connected to a duct 96 which communicates with the apex of the upper hood 89. After the hot dry bags emerge from these rollers they may be fed through a

similar device in which the rollers are fed with cold water and cool dry air is fed through the pressing tables to cool the hot bags.

The travel of the bags through the inner drum 26 is effected by accelerating or decelerating the speed of rotation of the drum 26, and also upon the rate and magnitude of deceleration. The decelerating of the speed of rotation of the drum 26 is effected sharply so that the wet or partially dried bags engaging the conveying rib 68 will slide along the inner surface of the drum 26, being moved longitudinally thereof by reason of the pitch of the rib 68. It will be understood that the drum 26 is continuously rotated, and that the lowest speed of rotation thereof is sufficient to centrifugally maintain the bags within the drum 26 against the inner surface thereof. The rate of travel of the bags through the drum 26 will depend in part upon the frequency of the periods of acceleration and deceleration thereof, in part upon the pitch of the conveying rib 68, and the rate and magnitude of deceleration.

In order to effect the desired travel of the bags through the drum 26, I have provided a periodic control means for the motor 75, and in Fig. 7 there is shown a diagrammatic view of the electric circuits connected to the motor 75 for effecting this result. As is well known in the art, when resistance is inserted in series with the shunt field of an electric motor, thus reducing the field current, the motor speed is increased, and conversely when the field current is increased the motor slows down. In Fig. 7 the armature of the motor 75 is designated 97 and the field 98. A pair of wires 100 and 101 connect the armature 97 with a pair of current supply wires 102 and 103, respectively, and a double pole switch 104 is interposed in the supply wires 102 and 103. The supply wire 102 is connected to one end of a rheostat resistance wire 105, and the supply wire 103 is connected to one side of the field 98. The opposite side of the field 98 is connected by a wire 106 to the opposite end of the resistance 105, and a wire 107 connects the wire 106 with the wiper 108 which wipes over the resistance 105.

The wiper 108 is rotated continuously by means of an operator 109 which is here shown as a small electric motor having a driving pulley 110 about which a belt 111 is trained. A driven pulley 112 is carried by the wiper 108 so that rotation of the driving pulley 110 will effect clockwise rotation of the wiper 108. As the wiper 108 first engages the resistance 105 the current will flow from the wire 102 through the first portion of the resistance 105, the wiper 108, and wires 107 and 106 to the field 98, the circuit being completed through the field 98 and supply wire 103. At this time little or no resistance is interposed between the supply wire 102 and the field 98 so that the motor 75 will abruptly slow down. As the wiper 108 moves around the resistance 105 the amount of resistance interposed in the field 98 will be increased, thus effecting a speeding-up of the motor 75. At the time the wiper 108 reaches the end of the resistance 105 the maximum amount of resistance is interposed in the field 98 so that the motor 75 will be rotated at its highest speed. This high speed of the motor 75 will continue for one-half revolution of the wiper 108, during which time the wiper 108 is disengaged from the resistance 105. When the wiper 108 is disengaged from the resistance 105 the current will flow from the supply wire 102 through the resistance 105 and wire 106 to the field 98, and thence to the other supply wire 103.

While I have shown a motor 109 as an operator for the wiper 108, it will be understood that any other suitable means may be provided for effecting continuous rotation of the wiper.

In order to provide a means whereby clean or fresh water may be supplied to the housing 11, I have provided an automatically operable control means shown in Fig. 3 which is connected to the solenoid operated valve 56. A pipe 113 is connected at one end to the housing 11 at a point forwardly of the wall or baffle 35 and beneath the drying zone 69 of the drum 26. The opposite end of the pipe 113 is connected to a receiver 114 which is open at the upper end thereof. A valve 115 may be interposed in the pipe 113 between the housing 11 and the receiver 114. An outer casing 116 is disposed about the receiver 114, being substantially higher than the receiver 114 so that the liquid from the receiver 114 may overflow into the casing 116. A drain pipe 117 is connected to the casing 116 and is adapted to carry off the overflowing water or liquid.

A hydrometer 118 is disposed within the receiver 114 and is provided with an upwardly projecting stem 119 carrying a shutter 120. A light source 121 is disposed above the normal level of the shutter 120 and projects a beam of light through a screen 122 in the direction of a photo-electric cell 123. The cell is connected at one side thereof to the wire 57 and at the other side by a wire 124 to a battery 125 or other suitable source of current supply. The wire 58 is connected to the battery 125, so that when the cell 123 is cut off from the light beam a circuit will be completed from the battery 125 to the solenoid 126 associated with the valve 56 and this valve thus moved to an open position. It will be understood that if desired or necessary a suitable relay may be placed in circuit with the light cell 123 to effect opening and closing of the circuit from the battery 125 to the solenoid 126 through the wires 57, 58 and 124.

In Figure 8 there is disclosed a modified form of drum structure, wherein the drum 26a is provided with a plurality of inclined openings 27a which are inclined in a direction to force the water into the drum 26a during the rotation of the drum. In order to assist in forcing the water through the openings, the drum 26a is provided on the exterior thereof with a blade or vane 127 for each opening 27a which serves to pick up the water and force the water inwardly through the opening 27a.

In Fig. 9 there is disclosed an alternate control means for the washing drum which is mounted adjacent the stationary drum 11a. The drum or housing 11a is supported from supporting beams 20a which are vertically adjustable by means of a nut 25a which is threaded onto a threaded support 23a. The support or shaft 23a is pivotally mounted as at 24a onto the base 10a. The housing 11a is provided with a discharge member 78a supported by means of supporting bars 79a forwardly of the adjacent end of the housing 11a. The inner drum 26a is provided with a grooved pulley 70a about which belts 72a are trained, and these belts 72a are also trained about a driving pulley 73a mounted on the shaft 74a of a motor 75a. The motor 75a is mounted on a platform 76a which is supported on beams or bars 77a extending transversely of the beams 20a.

A variable speed transmission 130 is interposed between the pulley 73a and the motor 75a, the transmission 130 being of conventional type and capable of providing the desired high and

low speeds for the pulley 73a with the motor 75a operating at a constant speed. A transmission shifting lever 131 is connected at one end to the shifting means of the transmission 130, and the other end of the shifting lever 131 is connected to the outer end of a piston rod 132. An air cylinder 133 having a piston 134 slidably therein is mounted adjacent the motor 75a, the piston 134 being secured to the inner end of the connecting or piston rod 132.

The cylinder 133 is provided with a pair of spaced apart air intake ports 128 and 129 adjacent each end thereof, and air pipes 136 and 135, respectively, are connected to the ports 128 and 129. The pipe 135 is connected to a three way valve member 139, which is shown diagrammatically, and a pressure reducing valve 137 is interposed in the pipe 135 between the cylinder 133 and the valve 139. The pipe 136 is connected to the valve 139, and a pressure reducing valve 138 is interposed in the pipe 136. By means of these valves 137 and 138 the amount of air supplied to the cylinder 133 on opposite sides of the piston 134 can be very finely regulated so that the operating lever 131 can be rocked in either direction at the desired equal or differential speeds. The valve 139 is provided with a vent 140 so that when air is admitted to the cylinder 133 at one side of the piston 134 to move the piston 134 in one direction, the air on the opposite side of the piston 134 may exhaust into the atmosphere. An air supply pipe 147 is connected at one end to the valve 139, and at the other end to a suitable source of air supply.

The valve 139 is operated to communicate either the pipe 135 or the pipe 136 with the pipe 147 by means of a timer 146. This timer 146 is here shown diagrammatically, and may be a conventional timer which is adapted to periodically open and close a switch structure incorporated within the timer. A solenoid coil 142 is connected to the timer 146, and a battery 145 is also connected to the timer 146 so as to periodically energize the solenoid coil 142. A solenoid core 142a is connected to a valve lever 141 which is secured to the valve 139, so that when the coil 142 is energized the core 142a will be drawn inwardly of the coil 142 and the lever 141 will be rocked in a counterclockwise direction and thus communicate the pipe 135 with the supply pipe 147 and communicate the pipe 136 with the vent 140. A spring 143 is secured at one end as at 144 to the housing 11a and at the other end to the upper end of the lever 141, and constantly urges the lever 141 to rock the valve plug in a clockwise direction and communicate the pipe 136 with the pipe 147.

In the use and operation of this cleaning and drying structure, the bags to be cleaned are discharged into the lower intake end of the housing 11 through the intake opening 15 from a chute 127a. This lower end of the housing 11 will have a greater concentrate of sugar than the succeeding chambers defined by the baffles or partitions 37, 36 and 35. The speed of rotation of the drum 26 is periodically accelerated and decelerated by means of the control structure shown in Fig. 7 or in Fig. 9, so that the bags within the drum 26 will be conveyed therealong by means of the conveying rib 68. The speed of longitudinal movement of the bags in the cleaning zone will be substantially greater due to the pitch of the rib 68 than the speed of movement in the drying zone 69. The openings 27 in the drum 26 in the upper portion of the wet zone are so ar-

ranged that the water in the bags will be centrifugally forced out of the bags to some extent before the bags reach the drying zone. The lower portion of the housing 11 is filled with water to the level controlled by the float 61, and after the bags have passed through the drum 26 there will be a considerable concentrate of sugar within the water positioned in all of the chambers defined by the baffles or partitions 35, 36 and 37. The concentrate of sugar in the water, however, will be less in the chambers succeeding the lowermost chamber, but when the quantity of sugar in the water in the foremost chamber becomes excessive, the water in the pipe 113 and in the receiver 114 will cause the hydrometer 118 to rise and bring the shutter 119 between the light 121 and the cell 123. At this time the circuit to the solenoid 126 will be closed so that the solenoid associated with the valve 56 will effect an opening of the valve 56 so as to admit clean water into the housing 11. The admission of additional water in the housing 11 will likewise effect an upward movement of the float 61 which will in turn open the valve 59 to drain out the excess water. In this manner a constant level of water will be maintained in the housing 11. The arrangement of the baffles 35, 36 and 37 in the housing 11 is such as to prevent the incoming fresh and clean water from flowing directly to the valve 59.

When the cleaned and centrifugally dried bags are conveyed to the receiving member 78 they may be manually placed on the table 83 and pushed forwardly to the rollers 88 and 90. The rollers 88 and 90 will convey the bags through the drying member 84 where hot air is passed through the bags in order that the bags discharged from the drying member 84 will be thoroughly dried and ready for further use.

During the rotation of the cylinder 26, the bags in the washing zone 41, wherein the openings 27 are slanted in a direction to force the water into the cylinder, will first be subjected to the force of the incoming water in the submerged portion of the cylinder, and when the cylinder 26 carries the bags above the water, the centrifugal force developed by the rotation of the cylinder 26 will cause at least a portion of the water initially forced inwardly through the bags to reverse its movement. In this manner there will be a back and forth movement of the water during the time the bags are in the washing zone and wherein the openings 27 are inclined as shown in Fig. 3. This back and forth movement of the water will effect a more thorough washing of the bags than has been heretofore possible.

When the bags pass the washing zone 41 and enter the drying zone 69, where the inclination of the openings 28 is reversed from the openings 27, the remaining water in the bags will be centrifugally forced out of the openings 28, and the inclination of these openings 28 is also such as to set up a suction which will assist the centrifugal action in forcing the water out of the bags. The beginning of the drying zone 69 is in substantially the middle of the cylinder 26, that is midway between the ends thereof, and at this point the cylinder 26 is still partially submerged in the water.

A cleaning and drying structure embodying this invention will thoroughly clean and dry the bags with the cleaning and centrifugally operated drying means actuated automatically so as to provide a continuous movement of the bags through the machine. The hereinbefore de-

scribed apparatus will also effect a uniformity in the cleaning of the bags due to the automatic changing of the water in the outer housing, and the uniformity of the movement of the bags through the inner rotating cylinder 26.

The rate of the movement of the bags may be readily varied by changing the time interval between the periods of abrupt speed change, varying the abruptness of the speed changes, or varying the magnitude of the speed changes. The magnitude may be changed by, as an example, increasing the lower speed period and decreasing the higher speed period, or vice versa. In the form shown in Figs. 1 to 7, this may be done by varying the rotation of the wiper 108, increasing or decreasing the resistance 105, providing a longer or shorter non-resistance strip at the initial contact of the wiper 108, or providing a variable speed for the wiper 108.

It is, of course, understood that various changes and modifications may be made in the details of construction of this invention, such changes and modifications being restricted only by the scope of the appended claims.

What is claimed is:

1. A bag washing and cleaning machine comprising an outer housing having a pool of washing liquid, a cylindrical drum rotatably mounted in said housing and having a portion partially submerged in the pool of washing liquid to define a washing portion, means for continuously rotating said drum at such speed that the lowest speed of rotation of said drum is sufficient to maintain the bags within the drum against the inner surface thereof by centrifugal force, means in the washing portion of said drum for permitting washing liquid from the pool to be forced interiorly of said drum when passing through said pool of liquid, said means permitting centrifugal discharge of the washing liquid outwardly of said drum during the remaining portion of each revolution thereof, means for varying the speed of rotation of said drum, and means in said drum for moving the bags longitudinally of the drum simultaneously with the variation in the speed of rotation of said drum.

2. A bag washing and cleaning machine comprising an outer housing having a pool of washing liquid, a cylindrical drum rotatably mounted in said housing and having a portion partially submerged in the pool of washing liquid to define a washing portion, helical conveyor means fixed interiorly of said drum, means for continuously rotating said drum at such speed that the lowest speed of rotation of said drum is sufficient to maintain the bags within the drum against the inner surface thereof by centrifugal force, means for varying the speed of rotation of said drum to permit the bags to be moved longitudinally of the drum by said helical conveyor means, and means in the washing portion of said drum for permitting washing liquid from the pool to be forced interiorly of said drum when passing through said pool of liquid, said means permitting centrifugal discharge of the washing liquid outwardly of said drum during the remaining portion of each revolution thereof.

3. A bag washing and cleaning machine comprising an outer stationary housing disposed at an inclination to the horizontal and having a pool of washing liquid, an open ended cylindrical perforate drum rotatably mounted in said housing and having a portion partially submerged in the pool of washing liquid to define a washing portion, means rotatably supporting said drum in

said housing, means for continuously rotating said drum at such speed that the lowest speed of rotation of said drum is sufficient to maintain the bags within the drum against the inner surface thereof by centrifugal force, the perforations in the washing portion of said drum being inclined in the direction of rotation for permitting washing liquid from the pool to be forced interiorly of said drum when passing through said pool of liquid, said perforations permitting centrifugal discharge of the washing liquid outwardly of said drum during the remaining portion of each revolution thereof, a helical conveyor rib fixed to the interior of said drum, and means for abruptly varying the speed of rotation of said drum, to permit the bags to be moved longitudinally of the drum by said helical rib, the pitch of said rib in the washing portion of said drum varying from that in the drying portion of said drum, whereby the rate of movement of the bags is greater in one portion of the drum than in the other.

4. A bag washing and cleaning machine comprising an outer stationary housing disposed at an inclination to the horizontal and having a pool of washing liquid, an open ended cylindrical perforate drum in said housing having a washing portion at one end partially submerged in the pool of washing liquid and a drying portion at its other end above the level of the pool of washing liquid, means rotatably supporting said drum in said housing, means for continuously rotating said drum at such speed that the lowest speed of rotation of said drum is sufficient to maintain the bags within the drum against the inner surface thereof by centrifugal force, the perforations in the washing portion of said drum being inclined in the direction of rotation of the drum for permitting washing liquid from the pool to be forced interiorly of said drum for a portion of each revolution thereof, said perforations permitting centrifugal discharge of the washing liquid outwardly of said drum during the remaining portion of each revolution thereof, a helical conveyor rib fixed to the interior of said drum and extending substantially the entire length of the latter, means for abruptly varying the speed of rotation of said drum to permit the bags to be moved longitudinally of said drum by said helical rib, a stationary receiver at the uppermost end of said housing positioned to receive the bags from the drying portion of said drum, and means in said receiver for reducing the rotational velocity of the bags delivered thereto by said helical rib.

5. A bag washing and cleaning machine comprising an outer stationary housing having a pool of washing liquid, means supporting said housing on an inclination to the horizontal, an open ended perforate drum in said housing having a washing portion at one end partially submerged in the pool of washing liquid and a drying portion at its other end arranged above the level of the pool of washing liquid, means rotatably supporting said drum in said housing, a conveyor rib fixed to the interior of said drum, a power member operatively connected to said drum for continuous rotation of the latter at such speed that the lowest speed of rotation of said drum is sufficient to maintain the bags within the drum against the inner surface thereof by centrifugal force, the perforations in the washing portion of said drum being inclined in the direction of rotation for permitting washing liquid from the pool to be forced interiorly of

said drum for a portion of each revolution thereof and for permitting centrifugal discharge of the washing liquid outwardly of said drum during the remaining portion of each revolution thereof, a change speed mechanism correlated with said power member, and means for actuating said change speed mechanism at predetermined intervals, to permit the bags to be moved longitudinally of said drum by said conveyor rib.

6. A bag washing and cleaning machine comprising an outer housing having a pool of washing liquid, a cylindrical drum in said housing having a portion of length partially submerged in the pool of washing liquid to define a washing portion, said drum having another portion of length disposed above the level of the pool of liquid to define a drying portion, means for continuously rotating said drum at such speed that the lowest speed of rotation of said drum is sufficient to maintain the bags within the drum against the inner surface thereof by centrifugal force, means in the washing portion of said drum for permitting washing liquid from the pool to be forced interiorly of said drum for a portion of each revolution thereof, said means permitting centrifugal discharge of the washing liquid outwardly of said drum during the remaining portion of each revolution thereof, means in the drying portion of said drum permitting continuous centrifugal discharge of washing liquid outwardly of said drum, a helical conveyor in said drum, and means for intermittently and abruptly decreasing the speed of rotation of said drum and alternately and gradually increasing the speed of rotation thereof, to permit the bags to be moved longitudinally of said drum by said helical conveyor.

7. A material washing and cleaning machine comprising an outer housing having a pool of washing liquid, a cylindrical drum in said housing having a portion of length partially submerged in the pool of washing liquid to define a washing portion, said drum having another portion of length disposed above the level of the pool of liquid to define a drying portion, means for continuously rotating said drum at such speed that the lowest speed of rotation of said drum is sufficient to maintain the material within the drum against the inner surface thereof by centrifugal force, means in the washing portion of said drum for permitting washing liquid from the pool to be forced interiorly of said drum for a portion of each revolution thereof, said means permitting centrifugal discharge of the washing liquid outwardly of said drum during the remaining portion of each revolution thereof, means in the drying portion of said drum for permitting continuous centrifugal discharge of the washing liquid outwardly of said drum, means for varying the speed of rotation of said drum, means in said drum for moving the material longitudinally of the drum upon variation of the speed of rotation of said drum, and means for periodically introducing washing liquid to said housing.

8. A material washing and cleaning machine comprising an outer housing having a pool of washing liquid, a cylindrical drum in said housing having a portion of length partially submerged in the pool of washing liquid to define a washing portion, said drum having another portion of length disposed above the level of the pool of liquid to define a drying portion, means for continuously rotating said drum at such speed that the lowest speed of rotation of said

drum is sufficient to maintain the material within the drum against the inner surface thereof by centrifugal force, means in the washing portion of said drum for permitting washing liquid from the pool to be forced interiorly of said drum for a portion of each revolution thereof, said means permitting centrifugal discharge of the washing liquid outwardly of said drum during the remaining portion of each revolution thereof, means in the drying portion of same drum for permitting continuous centrifugal discharge of the washing liquid outwardly of said drum, means for varying the speed of rotation of said drum, a helical member fixed interiorly of said drum for moving the material longitudinally of the drum simultaneously with the variation in the speed of rotation of said drum, means for periodically discharging washing liquid from said pool, and means for periodically introducing fresh washing liquid to said housing.

9. A material washing and cleaning machine comprising an outer stationary housing having a pool of washing liquid, means supporting said housing on an inclination to the horizontal, said housing having an inlet opening at the lower end thereof and an outlet opening at the upper end thereof, an open ended cylindrical perforate drum in said housing, having a washing portion partially submerged in the pool of washing liquid and a drying portion disposed above the level of the pool of washing liquid, means rotatably supporting said drum in said housing, means for continuously rotating said drum at such speed that the lowest speed of rotation of said drum is sufficient to maintain the material within the drum against the inner surface thereof by centrifugal force, the perforations in the washing portion of said drum being inclined in the direction of rotation for permitting washing liquid from the pool to be forced interiorly of said drum for a portion of each revolution thereof and for permitting centrifugal discharge of the washing liquid outwardly of said drum during the remaining portion of each revolution thereof, the perforations in the drying portion of said drum permitting continuous centrifugal discharge of washing liquid outwardly of the drum, a helical conveyor rib fixed to the interior of said drum, and means for varying the speed of rotation of said drum to permit the material to be moved longitudinally of the drum by said helical rib.

10. A bag washing and cleaning machine comprising an outer cylindrical housing having a pool of washing liquid, means supporting said housing on an inclination to the horizontal, an open ended cylindrical perforate drum in said housing having a washing portion adjacent one end thereof partially submerged in the pool of washing liquid and a drying portion adjacent its other end disposed above the level of the pool of washing liquid, means rotatably supporting said drum in said housing, means for continuously rotating said drum at such speed that the lowest speed of rotation of said drum is sufficient to maintain the bags within the drum against the inner surface thereof by centrifugal force, the perforations in the washing portion of said drum being inclined in the direction of rotation for permitting washing liquid from the pool to be forced interiorly of said drum for a portion of each revolution thereof and for permitting centrifugal discharge of the washing liquid outwardly of said drum during the remain-

ing portion of each revolution thereof, the perforations in the drying portion of said drum being inclined in the opposite direction for permitting continuous centrifugal discharge of washing liquid outwardly of said drum, a helical conveyor rib fixed to the interior of said drum, means for abruptly varying the speed of rotation of said drum to permit movement of the bags longitudinally of the drum by said rib, said drum having a diameter substantially less than the diameter of said housing, arcuate baffle means dividing the bottom portion of the space between said drum and said housing into a plurality of washing liquid compartments, means for periodically introducing washing liquid into one of said compartments and means for periodically discharging washing liquid from another one of said compartments.

11. A bag washing and cleaning machine comprising an outer stationary housing having a pool of washing liquid, means supporting said housing on an inclination to the horizontal, an open ended cylindrical perforate drum in said housing, having a washing portion partially submerged in the pool of washing liquid and a drying portion disposed above the level of the pool of washing liquid, a plurality of annular track members fixed to the outer surface of said drum, a plurality of rollers rotatably carried by said housing and engaging said track members to support said drum, certain of said rollers engaging the side walls of said track members to thereby hold said drum against endwise movement in at least one direction, means for continuously rotating said drum at such speed that the lowest speed of rotation is sufficient to maintain the bags within the drum against the inner surface thereof by centrifugal force, the perforations in the washing portion of said drum being inclined in the direction of rotation for permitting washing liquid from the pool to be forced interiorly of said drum for a portion of each revolution thereof and for permitting centrifugal discharge of the washing liquid outwardly of said drum during the remaining portion of each revolution thereof, the perforations in the drying portion of said drum permitting continuous centrifugal discharge of washing liquid outwardly of said drum, a helical conveyor rib fixed to the interior of said drum, and means for abruptly varying the speed of rotation of said drum for moving the bags longitudinally of the drum, and means for introducing clean washing liquid in said housing.

12. A bag washing and cleaning machine comprising an outer stationary housing having a pool of washing liquid, a cylindrical washing and drying drum in said housing, the washing portion of said drum being partially submerged in the pool of washing liquid and the drying portion thereof being disposed above the level of the pool of washing liquid, a helical rib fixed interiorly of said drum, means for continuously rotating said drum at such speed that the lowest speed of rotation of said drum is sufficient to maintain the bags within the drum against the inner surface thereof by centrifugal force, said drum being perforated in the washing and drying portions thereof, the perforations in the washing portion of the drum being inclined in the direction of rotation, vanes projecting outwardly from the periphery of said drum adjacent the perforations in the washing portion thereof for forcing washing liquid interiorly of said drum through said perforation for a portion of each

revolution of said drum, said perforations permitting centrifugal discharge of washing liquid outwardly of said drum during the remaining portion of each revolution thereof, the perforations in the drying portion of said drum being inclined in the opposite direction for permitting continuous centrifugal discharge of washing liquid outwardly of said drum, means for varying the speed of rotation of said drum to permit the bags to be moved longitudinally of the drum by said helical rib, and means for periodically introducing washing fluid into said housing.

13. A bag washing and cleaning machine comprising an outer stationary housing having a pool of washing liquid, means supporting said housing on an inclination to the horizontal, an open ended cylindrical perforate drum in said housing having a washing portion partially submerged in the pool of washing liquid and a drying portion above the level of said pool, means rotatably supporting said drum in said housing, means for continuously rotating said drum at such speed that the lowest speed of rotation is sufficient to maintain the bags within the drum against the inner surface thereof by centrifugal force, the perforations in the washing portion of said drum being inclined in the direction of rotation for permitting washing liquid from the pool to be forced interiorly of said drum for a portion of each revolution thereof and for permitting centrifugal discharge of the washing liquid outwardly of said drum during the remaining portion of each revolution thereof, the perforations in the drying portion of said drum being inclined in the opposite direction to permit continuous centrifugal discharge of liquid outwardly of said drum, a helical conveyor rib fixed to the interior of said drum, means for varying the speed of rotation of said drum for permitting movement of the bags longitudinally of the drum by said rib, the pitch of said rib in the washing portion of said drum being greater than that in the drying portion of the drum, whereby the bags are moved longitudinally through the washing portion of the drum at a faster rate than in the drying portion thereof, a stationary receiver carried by said housing at the uppermost end of the latter positioned to receive the bags from the drying portion of said drum, and a helical braking rib carried by said receiver to reduce the rotational velocity of the bags delivered thereto, the bags being delivered from the drum to the receiver with sufficient rotational velocity to cause them to advance by means of the rib in the receiver to an unloading station.

14. In a washing machine for bags and the like, a stationary housing having a body of washing liquid in the bottom thereof, a cylindrical drum rotatably mounted in said housing and having at least one portion thereof partially submerged in said body of washing liquid, and means for rotating said drum at a speed sufficient to maintain the bags against the inner surface of said drum by centrifugal force, said cylindrical drum being formed with means whereby washing liquid will be forced interiorly of said drum for a portion of each revolution thereof and centrifugally forced outwardly of said drum during the remaining portion of each revolution of the drum.

15. In a washing machine for bags and the like, a stationary housing having a body of washing liquid in the bottom thereof, a cylindrical drum rotatably mounted in said housing and having one end thereof partially submerged in

said body of washing liquid to form a bag-washing section, the other end of said drum being disposed above the level of the liquid in said housing and forming a bag-drying section, means for rotating said drum at a speed sufficient to maintain the bags against the inner surface of said drum by centrifugal force, said cylindrical drum having a series of openings in the bag-washing section thereof slanting in the direction of rotation of the drum, and means on the outer periphery of said drum co-acting with said slant-

ing openings to force washing liquid from the housing through said openings into the interior portion of each revolution of the latter, said openings centrifugally forcing part of the washing liquid outwardly of said drum during the remaining portion of each revolution, the drying-section of said drum having openings slanting in a direction opposite to the first-named openings to force the washing liquid out of the bags and outwardly of said drum.

JACOB J. NEUMAN.
